UNITED STATES PATENT OFFICE

HENRY RITHNER, OF WELLSBURG, WEST VIRGINIA

DESIGN FOR A CANDLE HOLDER

Application filed April 17, 1930. Serial No. 35,294. Term of patent 7 years.

To all whom it may concern:

Be it known that I, HENRY RITHNER, a citizen of the United States of America, and resident of Wellsburg, county of Brooke, and State of West Virginia, have invented a new, original, and ornamental Design for a Candle Holder, of which the following is a specification, reference being had to the accompanying drawings, in which—

I claim—
The ornamental design for a candle holder, as shown.

HENRY RITHNER.
